A. BOUCHERY,
CONNECTING PLUG,
APPLICATION FILED APR. 3, 1915.

1,217,143.

Patented Feb. 27, 1917.

Inventor
August Bouchery
By his Attorney John O. Seifert

UNITED STATES PATENT OFFICE.

AUGUST BOUCHERY, OF BROOKLYN, NEW YORK.

CONNECTING-PLUG.

1,217,143.

Specification of Letters Patent. Patented Feb. 27, 1917.

Application filed April 3, 1915. Serial No. 18,874.

To all whom it may concern:

Be it known that I, AUGUST BOUCHERY, a citizen of the United States, residing in the borough of Brooklyn, in the county of 5 Kings, city and State of New York, have invented new and useful Improvements in Connecting-Plugs, of which the following is a specification.

This invention relates to connecting plugs 10 to engage in the commercial screw threaded socket or the like to connect electrical conductors, and it is the primary object of the invention to provide a plug of this character which may be securely connected to and 15 disconnected from the screw threaded shell of a socket or the like by a longitudinal movement, and without the necessity of rotating the plug or any part associated therewith.

20 It is the principal object of the invention to provide a plug of this character consisting of a unit or integral construction, that is, constructed of a single block of suitable material, a contact yieldingly carried with-

25 in said block having a portion to project through an opening in and beyond the side of the block to co-operate with the screw threaded shell of a socket or the like to securely but removably retain the plug therein.

30 In the drawing accompanying and forming a part of this specification, Figure 1 is a perspective view, partly broken away, of a connecting plug illustrating an embodiment of my invention.

35 Fig. 2 is a sectional side elevation of the plug.

Fig. 3 is a plan view.

Fig. 4 is a view in perspective of the component contacting parts of the plug, showing in a diagrammatic manner the relation 40 of the contacts to the plug and the conductor connections thereto.

Fig. 5 is a perspective view of a finger-piece removably connected to one end of 45 the plug.

Fig. 6 is a perspective view, partly in section, showing a modified construction of plug; and

50 Fig. 7 is a sectional detail view illustrating the yielding contact in the form of a ball.

Similar characters of reference designate like parts throughout the different views of the drawing.

55 The embodiment of my invention shown

in the drawing comprising a block 7 of suitable insulating material, such as vulcanite or porcelain, of a diameter to readily pass into the screw threaded shell 7' of a socket, such as a lamp socket (shown in a general 60 way by S), said block having a central contacting element 8 at one end in the form of a disk or washer held to the block by a screw engaging in the block, and which contact is adapted to engage the contact 8' in the 65 socket located centrally thereof. One of the conductor wires 9 is connected to said contact, said conductor passing through a longitudinal aperture or bore 25 in the block adjacent said contact, a channel or recess extending from said aperture to the contact so that the conductor will be within the outer 70 contour of the block, as clearly shown in Fig. 1.

A contact in the form of a shouldered plug 75 or plunger, although this may be in the form of a ball if desired, as shown in Fig. 7, is movably mounted in an aperture or bore 11 extending transversely through the block. One end of the aperture is provided with an 80 obstruction in the form of a washer or eyelet 12 concentric with said aperture, the opening in which obstruction is of less diameter than the diameter of the aperture and through which the reduced end of the 85 plunger passes so that a portion thereof may extend beyond the side of the block, the shoulder of the plunger engaging with said obstruction 12 preventing the same 90 from passing out of the aperture. The plunger is yieldingly forced through the opening in the obstruction by a spring 13 in the aperture, one end of which engages the plunger and confined within the aperture by a metallic plate 14 closing the opposite end of 95 the aperture, the said plate being located within a recess 15 within the block so that it will be within the outer contour of the block and secured in position by a bolt 16 passing 100 through the block and having screw threaded connection therewith with the head of the bolt engaging in a countersink in the block. The contact 10 is adapted to engage with the screw threaded shell of the socket, the electric circuit being through the washer, 105 the spring and plate and through conductor wire 17 connected to said plate through the instrumentality of a screw 18. The electric circuit is not only completed through the contact 10 but this contact also serves as the 110

means to securely and removably retain the plug in the socket.

A cap or finger-piece 20 is removably connected to the block as by means of screw threads, as shown at 21, (Figs. 1 and 2). The free end of this finger-piece is reduced at opposite sides, as at 22, 22, to provide a grip to readily remove the same, and has an aperture 23, the inner end of which is countersunk, (Figs. 1, 2 and 5). The finger-piece is so constituted that there is a space between the same and the block, as shown at 24, with which the bore 25 and the recess 15 communicate to permit of the free passage of the conductors 9 and 17, the conductors being knotted as shown in Fig. 1, and engaging in the countersunk portion of the aperture 23.

In the operation of inserting the plug into a socket, the plug is pushed longitudinally therein until the end of the plug is seated therein with the contact 8 engaging with the socket contact 8', the contact 10 moving back and forth against the tension of the spring 13 as it rides over the screw threads of the socket shell. When the plug is seated the contact is forced or moved outward by the spring 13 and caused to engage with the screw threads of the socket shell firmly and securely holding the plug in place, as shown in Fig. 2. To remove the plug it is only necessary to grasp the cap 20 and exert an outward pull when the plug may be readily withdrawn from the socket. To connect the conductors 9 and 17 to the contacts the said conductors are first threaded through the aperture in the cap and knotted. The conductor 9 is then threaded through the aperture 25 and the conductor 17 positioned to lie in the recess 15 when the cap is secured to the block and the conductors connected with the contacts. Should the plug be removed by a pull on the conductors it will be obvious that by the provision of the knot in said conductors any strain will come upon the cap through said knot and that there will be no strain exerted upon the contacts.

In Fig. 6 I have shown a construction in which the cap portion is integral with the block. In this construction the aperture 23 and the space 24 with which the bore 25 and recess 16 communicate are cored into the block when it is molded.

Instead of employing a shouldered plunger as shown in Fig. 2, the contact 10 may be in the form of a ball as shown in Fig. 7, in which case the end of the aperture 11 is tapered thereby preventing the ball from falling out. It will be obvious that this same construction can be employed in connection with the shouldered plunger. While I have shown only a single holding contact two or more may be employed with equal facility.

Variations may be resorted to within the scope of my invention.

Having thus described my invention, I claim:

1. A plug comprising a block of insulating material, a contact movably carried within said block having a portion to project through an opening in the side of the block, yielding means within the block to yieldingly force the contact through the opening, and means carried by the block to retain the yielding means in the block and coöperate therewith to complete the circuit, substantially as and for the purpose specified. 70

2. A plug comprising a block of insulating material, a contact movably carried within the block, a portion of which contact is adapted to project through an opening in the side of the block, means within the block to yieldingly force the contact through the opening, and means within the outer contour of the block to which a current conductor is adapted to be connected to retain the yielding means in the block and coöperate therewith to complete the circuit, substantially as and for the purpose specified. 80

3. A plug comprising a block of insulating material having an aperture extending transversely therethrough, and a contact movably carried in said aperture to constitute the means to retain the plug in the socket. 90

4. A plug comprising a block of insulating material having an aperture extending transversely therethrough, a contact element carried at one end of said block, and a contact yieldingly mounted in the aperture, substantially as and for the purpose specified. 100

5. A plug comprising a block of insulating material having an aperture extending transversely therethrough, a contact element carried at one end of the block, a contact movably mounted in the aperture adapted to have a portion to project beyond the side of the block, and yielding means within said aperture to coöperate with the contact, substantially as and for the purpose specified. 105

6. A plug comprising a block of insulating material having apertures extending longitudinally and transversely therethrough, a contact at one end of the block adjacent the longitudinal aperture, and a contact yieldingly mounted in the transverse aperture adapted to have a portion project beyond the side of the block, substantially as and for the purpose specified. 110

7. A plug having a block of insulating material having apertures extending longitudinally and transversely therethrough, a contact at one end of the block adjacent the longitudinal aperture, a contact yieldingly mounted in the transverse aperture, a portion of which normally projects beyond the side of the block, and an apertured finger- 115

piece removably connected to the end of the block, substantially as and for the purpose specified.

8. A plug comprising a block of insulating material having apertures extending longitudinally and transversely therethrough and a recess in the side extending from the transverse aperture to one end of the block, a contact at one end of the block adjacent the longitudinal aperture, a contact yieldingly mounted in the transverse aperture normally having a portion extending beyond the side of the block to coöperate with a socket to retain the plug therein, and a finger-piece removably connected to the end of the block having an aperture communicating with the longitudinal aperture and the recess in the block, substantially as and for the purpose specified.
- 10 9. A plug comprising a block of insulating material having apertures extending transversely and longitudinally there-
- through and a recess in the side extending from the transverse aperture to one end of the block; a contact at one end of the block adjacent the longitudinal aperture and to which a current conductor passing through the longitudinal aperture is adapted to be connected; a contact movably mounted in the transverse aperture adapted to have a portion extend beyond the side of the block; a spring in the transverse aperture to yieldingly coöperate with the said contact; a plate of conductor material in the block recess to which a current conductor engaging in the recess is adapted to be connected and to retain the spring in the aperture and coöperate therewith to complete the circuit; and a finger-piece removably connected to the end of the block having an aperture for the passage of the current conductors and communicating with the longitudinal aperture and recess in the block.

AUGUST BOUCHERY.
